UNITED STATES PATENT OFFICE.

ANNA L. VILANDREE, OF NEW YORK, N. Y.

PETTICOAT AND PANTALET COMBINATION.

Application filed July 25, 1922. Serial No. 577,404.

To all whom it may concern:

Be it known that I, ANNA LOUISE VILANDREE, a citizen of the United States, residing at New York city, in the county of New York and State of New York, have invented certain new and useful Improvements in Petticoat and Pantalet Combination, of which the following is a specification.

10 This invention relates to improvements in wearing apparel and has for its object to provide a combination skirt or petticoat and drawers for women.

13 Another object of the invention is to provide a petticoat so formed as to function as two separate and distinct garments.

20 A still further object of the invention is to provide a petticoat with a panel extending substantially half way up its back and front center and then transversely across the garment.

25 Another object of the invention is to provide a petticoat with means whereby it cannot be inverted either by a gust of wind or through centrifugal force caused by dancing around of the wearer.

30 With the above and such other objects in view as may hereinafter more fully appear, I have invented the garment illustrated in the accompanying drawings, in which—

Figure 1 is an elevational view of my garment;

35 Figure 2 is a sectional view taken on line 2—2 thereof;

Figure 3 is a transverse sectional view taken on line 3—3 of Figure 1;

40 Figure 4 is a longitudinal sectional view taken on line 4—4 of Figure 2, showing a modification of the invention; and

Figure 5 is a similar view, a panel being unfastened at one end and dropped down.

45 Like reference characters indicate like parts throughout the following specification and in the several views in the drawings, in which 1 is a petticoat or underskirt, having a facing 2, extending entirely around its bottom edges on the inside thereof, the said facing at its central front and rear portions having extensions 3 and 4 which project substantially half-way up the garment to about the point 5, to which point the lower edge of the corsets of the wearer extends. These extensions form panels 50 which are stitched to the body 6 of the garment, the double thickness of the material

acting to effectually prevent the passage of light through the garment so as to outline the legs of the wearer. The upper edges of said panels 4 and 6 terminate in a transverse loose panel section 7, extending across the substantially center portion of the garment, said panel 7 being adapted to project between the legs of the wearer, whereby the garment is formed into a combination 60 skirt and drawers. The panel 7 may be of a length equal to the full width of the skirt at the point of the skirt to which the panel is attached in order that the skirt will not be drawn together at any point by 65 the panel, or it may be shorter if desired.

In Figures 4 and 5, I show a slight modification of the garment in which the transverse panel 7^a is not formed integral with the panel 3^a, however its ends 8 and 11 are secured to the upper ends 9 and 12 of the panels 3^a and 4^a, by means of buttons 10 and 13, hooks and eyes, clasps or other suitable means, in order that instead of having to put the garment on as a pair of 70 drawers, it may be slipped over the head of the wearer as is a petticoat, after which the transverse panel 7^a may be buttoned in place. This form of the invention also makes it more convenient garment for other 75 reasons. For instance, should the panel 7^a become soiled before the skirt of the garment is soiled, it may be removed and a clean panel substituted in place thereof, thus saving considerable unnecessary laundering. 80 In this form of the invention the panels 4^a and 3^a extend further up the front and back of the garment than in the first described form and has additional rows of buttons, hooks or clasps 14 and 15, in order that during the menstrual period, the panel 85 7^a may be fastened higher so as to fit close to the body of the wearer, said panel, in this case, forming a support to which a catamenial sack may be pinned or otherwise 90 secured.

Besides being a two-in-one garment, as above explained, this garment has a decided advantage in its transverse panel 7 in that in the use of this panel the petticoat cannot be inverted through a sudden gust of wind, a strong draft or through centrifugal motion as in dancing. A great disadvantage in dancing with loose garments on heretofore has been that in round dancing the wearer's skirts and petticoats will be thrown into inverted position through 100 105 110

centrifugal force. This garment, however, will positively prevent this to the great comfort of its wearer as the petticoat may be made full enough to be very comfortable in walking and dancing and yet, because of the transverse panel 7, it cannot "balloon" to an unseemly extent. Furthermore, the garment has another very material advantage over other combination garments in that because of the location of the panel 7, the edges and lower portion of the skirt are free, both adding to the appearance and comfort of the wearer, whereas, in garments such as "teddies" the lower edge of the garment is connected between the legs of the wearer, transforming the lower skirt portion of the garment substantially into drawer legs, which makes the garment uncomely or immodest in appearance if worn with a light weight dress through which it may be seen and also adds greatly to the discomfort of the wearer because she does not have the same free use of her legs as she will have in wearing a garment of the character above described.

Having described my invention that which I claim to be new and desire to procure by Letters Patent is:—

1. A skirt having a continuous side wall formed of a single thickness of material having an independent front centrally located shadow panel extending from the lower edge of said skirt to a point just below the abdominal portion of the skirt whereby only one thickness of material of the garment will cover the abdomen of the wearer, and a panel of like formation and extent on the back of said skirt opposite said first panel.
2. A petticoat having a transverse panel extending there-across, said panel being located substantially midway between the upper and lower edges of said petticoat, substantially vertical panels extending from said panel to the lower edge of said garment, said panels aligning in the central front and back portions of said garment, said panels terminating at their lower edges in facings, said panels being narrow relative to said petticoat, said facings extending

around the lower edge of said garment, said transverse panel having one end detachably connected to said petticoat, said panel being detachable at both ends from said petticoat, said panels being adjustable vertically ⁵⁵ on said petticoat.

3. In a petticoat a facing and relatively narrow opposingly disposed panels projecting upwardly, from said facing, a transverse panel connecting the ends of said first ⁶⁰ panels, said panel being detachable, and adjustable.

4. A garment consisting of a skirt having a transverse panel connected thereto above its lower edge, said panel being vertically adjustable on said skirt. ⁶⁵

5. A garment consisting of a skirt having a transverse panel connected thereto above its lower edge, said panel being vertically adjustable on said skirt, vertical ⁷⁰ panels stitched to said skirt to which said transverse panel is connected.

6. In a petticoat having a facing, a pair of oppositely disposed shadow panels projecting upwardly from the upper edge of ⁷⁵ said facing, said panels being relatively narrow, a transverse panel connecting the upper terminals of said first panels, said last panel being relatively narrow, and substantially the width of said first panels, said last panel being vertically adjustable relative to said skirt.

7. A skirt having a continuous side wall formed of a single thickness of material having an independent front centrally located shadow panel extending from the lower edge of said skirt to a point just below the abdominal portion of the skirt whereby only one thickness of material of the garment will cover the abdomen of the wearer, ⁸⁰ a panel of like formation and extent on the back of said skirt opposite said first panel and a transverse panel directly connecting the upper portions of said first panels.

In testimony whereof I affix my signature ⁸⁵ in the presence of two witnesses.

ANNA L. VILANDRER.
